(57) **CLAIM**

We claim the ornamental design for an external battery pack, as shown and described.

DESCRIPTION

FIG. 1 is a front perspective view of an external battery pack showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is another perspective view thereof; and,

FIG. 9 is a perspective view of the external battery pack, shown in an environment of use.

The broken lines in the figures depict environmental subject matter and form no part of the claimed design.
